WATER DEAERATION

Filed Feb. 16, 1938

FIG. 3

SECTION Y-Y

INVENTOR

LESTER M. GOLDSMITH

By *Wallace J. Smith*

ATTORNEY

UNITED STATES PATENT OFFICE

2,160,856

WATER DEAERATION

Lester M. Goldsmith, Philadelphia, Pa., assignor
to The Atlantic Refining Company, Philadelphia, Pa., a corporation of Pennsylvania

Application February 16, 1938, Serial No. 190,737

6 Claims. (Cl. 114—0.5).

The present invention relates to the deaeration of sea-water which may be employed as a cooling medium for ships' condensers, and relates more particularly to apparatus for accomplishing the removal of air entrained in sea-water taken aboard ship.

A principal object of this invention is the removal of entrained air from sea-water which may be employed as circulating water for ships' condensers, engines, coolers, sanitary system or as water supply for ships' evaporators. Since corrosion of condensing equipment, evaporators, coolers and the like appears to be due, at least in part, to the action of air or oxygen contained in sea-water, it is an object of this invention to remove, in a simple and economical manner, a substantial proportion of the air from the sea-water prior to use thereof aboard ship.

A further object of this invention is the provision of a deaerating chamber so fabricated as to utilize, to the maximum extent and with the least alteration, portions of the normal structure of the ship.

My invention may be illustrated with reference to the accompanying drawing, wherein Figure 1 shows, diagrammatically, a plan view of my deaerating chamber;

Figure 2 shows a longitudinal section of the chamber, taken along the line X—X of Fig. 1, and;

Figure 3 shows a transverse section of the chamber, taken along the line Y—Y of Fig. 1.

Referring to the drawing, in which corresponding elements are similarly numbered, there is provided a water-tight deaerating chamber (Fig. 1) defined by the lines A, B, C, D, E, F, G and H, between the ship's double-bottom, the upper bottom of which is designated as 1, the lower bottom as 2, and the ship's side as 3. Such chamber may be of any convenient size and shape to suit the structural and machinery arrangements of the ship, and is not necessarily limited to the contour shown in the drawing. Preferably the chamber is located under or near the ship's equipment being supplied with water so that deaerated water may be supplied from the chamber to said equipment with a minimum expenditure of energy. In constructing the chamber, use is made of the transverse frames 4 which are part of the ship's normal structure, i. e., those frames together with solid walls B—C, D—E and F—G and the ship's side A—H define the chamber A, B, C, D, E, F, G and H and form solid, water-tight walls between the upper and lower portions of the double-bottom. The frames 4 or portions thereof which lie

within the chamber (Fig. 1) are provided (Fig. 3) with perforations or openings 5, whereby free circulation of water within the chamber is permitted, and are further provided (Fig. 3) with openings 6 adjacent the top thereof and beneath the upper bottom 1 to permit free circulation of air de-entrained from the sea-water.

In order to bring sea-water into the deaerating chamber there is provided externally of the chamber a sea chest 7 opening into the sea 10 through the lower bottom 2. Such sea chest is connected to the deaerating chamber by means of a gate valve 8 and a conduit 9, said conduit preferably having a progressively increasing cross-sectional area from said valve to the point of junction with said chamber. The divergent shape of the conduit 9 causes a diminution of velocity of the sea-water entering through the sea-chest and assists in effecting de-entrainment of air taken in with the sea-water.

The deaerating chamber is additionally provided with circulating pumps 10 for withdrawing deaerated water from the chamber and supplying same to the ship's condenser system. In order to remove from the chamber air which has been de-entrained from the incoming sea-water, there are provided one or more vent pipes 11 which communicate with said chamber through the upper bottom 1 and extend upwardly a sufficient distance to be safely above the ship's water-line. 30 Access to the deaerating chamber is attained through a water-tight manhole 12 in the top of the chamber, i. e., the upper bottom 1. To facilitate removal of substantially all the sea-water contained in the chamber in the event that it becomes necessary to inspect or repair the chamber, a suction pipe 13 is provided and may be connected to a bilge pump (not shown).

In the operation of the deaerating chamber, a controlled quantity of sea-water containing entrained air is continuously or intermittently admitted into the chamber by means of the sea chest 7, valve 8 and conduit 9. Within the chamber, the water, by reason of the relatively large volume of the chamber and by impingement against the chamber walls and the perforated frames, is brought to a state sufficiently quiescent that entrained air bubbles coalesce and pass from the water into the air space above the water level in the chamber. The de-entrained air collecting above the water is removed from the upper portion of the chamber by means of the vent pipes 9, and the deaerated water is withdrawn from the chamber by means of circulating pumps 10 and passed to the ship's condensers as a cooling medi-

um, or otherwise utilized as necessity dictates. In this manner a substantial quantity of the air entrained in the sea-water brought aboard ship is removed, thereby effecting a decrease in corrosion of ship's equipment utilizing such deaerated water.

When in the appended claims, the term "sea-water" is employed, it is to be understood to mean water from any source that may be employed for the purposes described, whether it be salt water or fresh water.

What I claim is:

1. In ship construction, means for deaerating sea-water comprising a water-tight chamber formed between the ship's double-bottom, a valve-controlled conduit connecting said chamber with the sea, a pump associated with said chamber for withdrawing deaerated sea-water therefrom, perforated frames disposed within said chamber to assist de-entrainment of air from sea-water impinging thereupon, and a vent for removing from said chamber air de-entrained from said sea-water.

2. In ship construction, means for deaerating sea-water comprising a water-tight chamber formed between the ship's double bottom, a sea-chest adjacent said chamber and opening into the sea, a valve-controlled conduit connecting said sea-chest with said chamber, a pump associated with said chamber for withdrawing deaerated sea-water therefrom, and a vent for removing from said chamber air de-entrained from said sea-water.

3. In ship construction, means for deaerating sea-water comprising a water-tight chamber formed between the ship's double-bottom, a sea-chest adjacent said chamber and opening into the sea, a valve-controlled conduit connecting said sea-chest with said chamber, transverse perforated frames disposed within said chamber to assist de-entrainment of air from sea-water impinging thereupon, and a vent for removing from said chamber air de-entrained from said sea-water.

4. In ship construction, means for deaerating sea-water comprising a water-tight chamber formed between the ship's double-bottom, a sea-chest adjacent said chamber and opening into the

sea, a valve-controlled conduit connecting said sea-chest with said chamber, said conduit having a progressively increasing cross-sectional area from said valve to the point of juncture with said chamber, frames comprising a portion of the ship's double-bottom structure extending transversely across said chamber, said frames being provided with perforations to permit free circulation of sea-water and de-entrained air in said chamber, and a vent for removing from said chamber air de-entrained from said sea-water.

5. In ship construction, an inner bottom, an outer bottom, water-tight walls between said bottoms forming a deaerating chamber, a valve-controlled conduit connecting said chamber with the sea, a pump associated with said chamber for withdrawing deaerated sea-water therefrom, frames within said chamber extending between said inner and outer bottoms and dividing said chamber into a plurality of compartments, openings in said frames to permit circulation of sea-water between said compartments, openings in the upper portion of said frames adjacent the inner bottom to permit circulation of air between said compartments, and a vent connected to the upper portion of said deaerating chamber, whereby air deentrained from the sea-water may pass from said chamber.

6. In ship construction, an inner bottom, an outer bottom, water-tight walls between said bottoms forming a deaerating chamber, said water-tight walls comprising, in part, normal frame structure of said ship, a valve-controlled conduit connecting said chamber with the sea, a pump associated with said chamber for withdrawing deaerated sea-water therefrom, frames within said chamber extending between said inner and outer bottoms and dividing said chamber into a plurality of compartments, openings in said frames to permit circulation of sea-water between said compartments, openings in the upper portion of said frames adjacent the inner bottom to permit circulation of air between said compartments, and a vent connected to the upper portion of said deaerating chamber, whereby air de-entrained from the sea-water may pass from said chamber.

LESTER M. GOLDSMITH.
